CLAIM

The ornamental design for a bell housing component for independent rear suspension system, as shown and described.

DESCRIPTION

FIG. 1 is a front elevational view of a bell housing component for independent rear suspension system;

FIG. 2 is a bottom plan view thereof;

FIG. 3 is a rear elevational view thereof;

FIG. 4 is a top plan view thereof;

FIG. 5 is a right side elevational view thereof, the left side being a mirror image of that shown; and,

FIG. 6 is a top and left side perspective view thereof.
